W. O. MELTON
RECEPTACLE CHARGER

Filed July 21, 1924

Inventor:
WILEY O. MELTON,

Ogle R. Singleton

Attorney

UNITED STATES PATENT OFFICE.

WILEY O. MELTON, OF ROCKY MOUNT, NORTH CAROLINA.

RECEPTACLE CHARGER.

Application filed July 21, 1924. Serial No. 727,257.

To all whom it may concern:

Be it known that I, WILEY O. MELTON, a citizen of the United States, residing in the city of Rocky Mount, in the county of Edgecomb, in the State of North Carolina, have invented certain new and useful Improvements in Receptacle Charges, of which the following is a specification.

My invention consists in a new and useful improvement in receptacle chargers and is designed more particularly for icing refrigerators of that type in which the ice chamber is located over the food chamber and at a considerable height above the floor level and has an ice capacity sufficiently large as to require that it be charged with one or more standard size ice blocks. The ordinary method of charging these ice chambers is to provide a block and fall by which the blocks of ice are hoisted to a point opposite the doorway of the elevated ice chamber. It is then necessary for the operator to enter the ice chamber, which process is difficult, uncomfortable and unsanitary, in order to draw the ice blocks through the doorway into the ice chamber. This is not easy and at times extremely dangerous. In order to permit the ice block to be drawn through the doorway, the block and fall must be eased off, the ice block being snatched in through the doorway. This often results in the block colliding with the sill of the doorway and if there be a fault in the ice block, the impact against the sill will cause the block to split, the portion outside of the doorway falling to cause serious damage.

It is to obviate this difficult and dangerous practice obtaining in the present method of charging ice chambers of large refrigerators that my invention is designed. My device comprises a stout but easily portable receiving platform upon which the blocks of ice may be positioned directly in front of the doorway of the ice chamber and from which they may be very easily caused to slide directly into the chamber by a pike pole or other suitable tool, the operator being relieved of the necessity of mounting to the elevation of the ice chamber. My device is provided with novel means for easily and quickly attaching the platform to the doorway of the ice chamber and for providing a substantial and effective connection at that point adequate to sustain the excessive strain imposed by the handling

of the heavy ice blocks. The platform is also provided with effective supporting means to insure its stability and also with suitable forwarding means to facilitate the delivery of the ice blocks to the ice chamber.

In the drawing filed herewith, I have illustrated one specific embodiment of my invention but it is to be distinctly understood that I do not consider my invention limited to the details of construction therein shown and hereinafter described, but refer for its scope to the claims appended hereto.

In the drawings:

Fig. 1 is a side elevation of my device. 70

Fig. 2 is a front elevation.

Fig. 3 is a top plan view.

Fig. 4 is a transverse section on the line 4—4 of Fig. 3.

Fig. 5 is a cross section on the line 5—5 75 of Fig. 4.

In the form of my device illustrated in the drawing, the platform is composed of sleepers 1 and floor boards 2. The outer end of each sleeper 1 is attached to a leg 3 which is slightly inclined from the perpendicular toward the platform. The upper end of each leg 3 is recessed on its inner face, as at 4, the recess having a horizontal face 5 and an oblique face 6 disposed parallel with the axis of the leg 3. The end of the sleeper 1 rests upon the face 5 of the recess in the leg 3 and has an oblique face 7 complementary to the oblique face 6 of the recess in the leg 3. The joint of the sleeper 1 and the leg 3 is overlaid by a plate 8 which is bolted to the sleeper 1 and the leg 3. Each sleeper 1, at its end opposite to that attached to the leg 3, has a recess 9 forming a tongue 10 at the lower side of the end. I provide 95 straps 11 overlying the floor boards 2 and above the sleepers 1. These straps 11 are bent downwardly over the floor board 2 above the junction of the sleepers 1 and the legs 3 and are extended downwardly overlying the upper ends of the legs 3. These straps 11 are fastened to the floor boards 2 and the sleepers 1 by bolts 12 positioned adjacent the ends of the sleepers 1 and are fastened to the legs 3 by bolts 13 passing 100 through the legs 3 adjacent their upper ends. These straps 11 extend somewhat beyond the ends of the sleepers 1 having the recesses 9 and terminate in downwardly turned keepers 14.

I provide at the inner end of the platform a roller 15 having its trunnions 16

journalized in the sleepers 1 and blocks 17 between the sleepers 1 and straps 11. The diameter of this roller 15 and its mounting in the sleepers 1 are such that it projects slightly above the upper surface of the floor boards 2.

The legs 3 are provided with tie rods 18 and may be provided with steps 19 to provide easy access to the platform. It is to be noted that the legs 3 are not only disposed at an inclination from the vertical relative to the platform but are also convergent from bottom to top, thus affording greater stability.

From the foregoing description of the structure of my device and its illustration in the drawing, its use will be obvious. When it is desired to supply ice to the ice chamber C, the block of ice I is hoisted by means of the ordinary hooks H and block and fall B until its lower edge is above the sill S of the doorway D of the ice chamber C. My device is then placed in position, the inner ends of the straps 11 passing over and resting upon the sill S and the keepers 14 engaging the inner edge of the sill S. At the same time, the tongues 10 bear against the apron A below the sill S, the recesses 9 receiving therein the outwardly extending portion of the sill S. The block of ice then being lowered and turned endwise toward the doorway D is received upon the platform of my device, its inner end

resting upon the roller 15. The hooks H are then disengaged from the ice block I, and, by means of a pike pole or other suitable tool, the ice block I is caused to slide from the platform, the roller 15 assisting, through the doorway D into the ice chamber C.

Having described my invention, what I claim is:

1. A receptacle charger comprising a portable platform provided with supporting means, and means for attachment within the opening of the receptacle, comprising sill-engaging keepers and apron-engaging tongues.

2. A receptacle charger comprising a platform, two supporting legs relatively convergent and inclined to the perpendicular relative to said platform, and rigidly attached thereto, and two retaining straps bolted to said legs and platform and provided with downwardly turned keepers.

3. In a receptacle charger, the combination of two supports; recesses in the upper ends thereof; sleepers having their ends received in said recesses, and provided at their opposite ends with recesses and tongues; floor boards on said sleepers; and straps bolted to said supports, sleepers and floor boards, and provided at their ends with downwardly turned keepers.

In testimony whereof I affix my signature.

WILEY O. MELTON.
